ATTORNEYS.

UNITED STATES PATENT OFFICE

GEORGE F. THOMPSON, OF ERIE, PENNSYLVANIA, ASSIGNOR TO G. H. WILLIAMS COMPANY, OF ERIE, PENNSYLVANIA, A CORPORATION OF PENNSYLVANIA

CLAMSHELL BUCKET

Application filed June 26, 1928, Serial No. 288,363. Renewed January 30, 1931.

Clam shell buckets are usually provided with a head and this is subjected to very severe duty. It is desirable to maintain it as of light construction as possible so as to keep the center of gravity on the bucket as a whole as low as possible. With the head of rigidity and shaped to receive its several parts the bucket may be made of greater stiffness so as to receive the strains to which it is subjected. In the present invention this head is formed of an integral casting, thus permitting the formation to receive the several parts and giving complete rigidity to the head as well as lightness. The invention further provides an improvement in the latch mechanism whereby the latch may be adjusted to remain locked under load and to automatically release as the load is released. Other features and details will appear more fully from the specification and claims.

A preferred embodiment of the invention is illustrated in the accompanying drawings as follows:

Fig. 1 shows a side elevation of the bucket, partly in section.

Fig. 2 an end view of the bucket.

Fig. 3 a section on the line 3-3 in Fig. 1.

Fig. 4 a side view of the head.

1 and 2 mark the bucket members. These are provided with arms 3 and 4 respectively and these are pivotally connected by a hinge pin 5. Links 6 are pivotally connected with the bucket member 2 by a pin 7. The links are riveted to a head 8. Links 9 are pivotally connected by a pin 10 with the bucket member 1 and pivotally connected to the head by a pin 10a. A catch block 11 is secured on the pin 5 and to the arms 4. This block has a catch shoulder 12 which is adapted to engage a latch 13. The latch 13 is pivotally mounted on a pin 13a arranged between the sides of a power arm 14, the power arm being pivotally mounted on the pin 7. A removable cam, or wearing plate 16 is mounted in the end of the latch plate and has a cam surface 16a engaging a roller 17 on the trip lever 18. The trip lever 18 extends from a trip block 19 journaled on a pin 20 extending between the sides of the power arm 14. A trip arm 21 extends from the block 19 and may

be manually operated by a trip line 22, the trip line extending through a pulley block 23 hung by a chain 24 from the head 8. A trip spring 25 is mounted on the trip arm 21 and is carried against a pad 26 mounted on a pad arm 27 extending from the head 8. The trip block has a positioning arm 28 with a roller 29 at its end which engages a plate 30 as the arm is swung to place, thus throwing the trip arm 18 out of the path of the cam block 16 so as to permit of the latch 13 hooking over the shoulder 12 with the bucket open and the arm swung down to position, this latch operating in the ordinary manner of such latches in buckets of this type. A stop 31 is also provided on the arm 28 which engages a stop 32 extending between the sides of the arm 14. This stop limits the movement of the trip arm.

The hook shoulder of the latch 12 is so designed that it tends to unhook under the load pressure and this unhooking is prevented by the trip lever 18 operating on the cam surface 16a. The operation of the cam surface to prevent the unhooking and still permit of the ready release is one of considerable nicety and the removable cam block 16 provides a means for maintaining this surface in its proper relation. As a further element in adjusting this means a set screw 33 is provided which extends through the arm 21 against the stop 32. By means of this set screw the position of the roller 17 on the cam surface 16a may be nicely adjusted.

In the operation of the device with the bucket in open position, the power arm is dropped down and the latch set, this operating in the usual manner. As the bucket is lifted and thus closed, pressure is placed on the latch 12 and this operating through the cam surface 16a on the trip 18 holds the trip 18 in position. As the bucket is closed, it places the spring 25 under tension, the force of the spring, however, being insufficient to force a tripping action of the trip arm so long as the load is on the latch, the cam surface being so designed to operate under the load as to require greater force than the spring to move it off the cam surface. When the load is lowered and the latch relieved of

the load the spring is then of sufficient force to swing the trip lever off the cam surface and release the latch so that when the bucket is again lifted it will open and discharge its contents. The bucket is operated from a single operating bridge 35 through the duplicate lines 34. The lines 34 operate over guide sheaves 36 on the power arm, sheaves 37 on the power arm, sheaves 38 on the head, sheaves 39 on the arm, and sheaves 40 on the arm and are secured on the block 11 by a clamp 41. A buffer stop 42 is arranged on the arm and this engages a head 43 carried by a sliding pin 44, the pin sliding through an opening 45 on the head and being yieldingly held in position by a spring 46. Nuts 47 at the outer end of the pin prevent its removal from the opening 45. This cushions the arm as it is brought up against the head.

20 The sheaves 38 are journaled on a pin 38a and the head 8 has pockets 8a formed in the sides thereof which receive the sheaves 38. The inner walls of these pockets are connected by a central block and the outer walls extend downwardly over the sheaves forming a housing for the sheaves and a webbing for strengthening the head. The pins 38a extend through the central block and outer walls of the pocket. The outer walls of the pocket not only form a bracing and housing for the sheaves but also a means for securing the links 6 and 9 to the head. This head is formed of one casting and this makes it feasible to connect the central block rigidly with the outer walls 8b and thus make a rigid connection between the fixed links 6. This gives to the entire structure rigidity. The central block forms a convenient position for the pad 27 and also for the buffer structure which is mounted on the central block. In this way the part of the bucket which is subjected to the greatest strain is given this added rigidity due to its integral structure, simplifies the forming of the housing and webbing of the head around the sheaves, and also a structure capable of taking the jars incident to the buffer structure.

What I claim as new is:—

1. In a clam shell bucket, the combination of bucket members; an integral head having a central block, sheave receiving pockets, and a sheave pin opening extending through the central block and the outer walls of the pockets; links pivotally connected to one of the bucket members and pivotally connected to the head; links pivotally connected to the other bucket member and rigidly secured to the head; sheaves in said pocket of the head; a sheave pin in the opening in the head on which the sheaves are mounted; and operating cables operating on said sheaves.

2. In a clam shell bucket, the combination of bucket members; a pivotal connection for said members; an integral head having a central block; sheave-receiving pockets and a

sheave pin opening extending through the central block and the outer walls of the pocket; links pivotally connected to one of the bucket members and pivotally connected to the head; links pivotally connected to the other bucket member and rigidly secured to the heads; sheaves in said pockets of the head; a sheave pin in the opening in the head on which the sheaves are journaled; a power arm; a latch between the arm and bucket members at the pivotal connection; and a trip mechanism for the latch comprising a spring on the power arm and a spring engaging pad on the central block.

3. In a clam shell bucket, the combination of bucket members; a pivotal connection between the members; a head; links extending from the head to the bucket members at points remote from the pivot; a power arm pivotally mounted on one of the bucket members; a latch mounted on the power arm; a hook connection between the latch and bucket members adjacent to the pivotal connection, said latch connection tending under load to disengage; a removable wearing block on the latch; a trip lever on the power arm operating on the latch, the engaging surfaces of the trip lever and latch tending to lock the trip lever against disengagement under pressure of the latch; a yielding thrust means between the trip lever and the head, said thrust means being brought into engagement with the closing of the bucket and throwing the trip lever upon a release of the load pressure; means for adjusting the trip lever relatively to the latch; and a cable connection extending between the head and the power arm.

4. In a clam shell bucket, the combination of bucket members; a pivotal connection between the members; a head; links extending from the head to the bucket members at points remote from the pivot; a power arm pivotally mounted on one of the bucket members; a latch mounted on the power arm; a hook connection between the latch and bucket members adjacent to the pivotal connection, said latch connection tending under load to disengage; a trip lever on the power arm operating on the latch, the engaging surfaces of the trip lever and latch tending to lock the trip lever against disengagement under pressure of the latch; means for adjusting the trip lever relatively to the latch; and a cable connection extending between the head and the power arm.

In testimony whereof I have hereunto set my hand.

GEORGE F. THOMPSON.
